MACHINE FOR HOLDING, STAMPING, AND DISPLAYING CHECKS.

No. 874,905.

Specification of Letters Patent.

Patented Dec. 24, 1907.

Application filed November 23, 1905. Serial No. 288,765.

To all whom it may concern:

Be it known that I, EDWARD FARRINGTON CHANDLER, a citizen of the United States, residing at Brooklyn, in the county of Kings and State of New York, have invented a new and useful Improvement in Machines for Holding, Stamping, and Displaying Checks, of which the following is a specification.

This invention relates to a machine for holding, stamping, and displaying checks, and has for its purpose to provide a device that is particularly adapted for use in banks to be used in connection with adding machines, and in which a stack of checks may be held and automatically segregated and conveyed past a stamping or indorsing cylinder and then held for a brief time in full view of the operator to enable him to read the numbers and record them upon the adding machine, after which the checks are finally deposited in a suitable receptacle from which they may be removed. This arrangement not only avoids the separate handling of the checks necessary when the amounts thereof are being recorded, but provides an automatic stamping device and insures each check being canceled without the necessity of individual handling upon the part of the operator and also gives him the use of both hands to operate the adding machine and thus permitting the work to be done in much less time than is now required.

Heretofore when the amounts of a number of checks were to be ascertained by the use of the adding machine to find out their gross amount, they have been deposited in a small tray or upon a small platform held adjacent the machine within easy reach and in full view of the operator so that he may read the amounts of the checks and with one hand operate the keys of the machine to record the amount, and the other hand, remove each check from the pile so that the second check may be read and the amount recorded. This arrangement constantly employs the use of one hand in turning the checks and consequently retards the work, and then after the amounts of one stack have been ascertained, the checks are stamped, necessitating a further handling and consequently the loss of much valuable time. With my machine, however, the manual labor of handling the checks when their amounts are being recorded and also when

stamping or indorsing them, is avoided, and consequently a saving of time and labor results.

It is, therefore, the object of my invention to provide a simple, efficient, and thoroughly practical machine for accomplishing the results hereinbefore stated, and with these briefly stated objects in view, the invention comprises certain details of construction and peculiar combination and arrangement of parts as will be fully described, in the following specification and pointed out in the claims, reference being had to the drawings, in which;

Figure 1 is a perspective view of my machine looking toward the front, and Fig. 2 is a similar view looking toward the back of the machine. Fig. 3 is a vertical longitudinal sectional view drawn on the line 3—3 of Fig. 4. Fig. 4 is a sectional elevation drawn on the line 4—4 of Fig. 3. Fig. 5 is an irregular horizontal section drawn on the line 5—5 of Fig. 3. Fig. 6, is a detail sectional view illustrating the gears for operating the various shafts hereinafter described. Fig. 7 is a detail longitudinal section drawn through the stamping cylinder. Fig. 8 is a detail cross-section drawn on the line 8—8 of Fig. 7, and Fig. 9 illustrates a portion of a check after it has passed through the machine and illustrating the stamp such as used in bands.

In the drawings A, designates the casing comprising a base A¹, sides, A², and front A³, the latter having an opening that is covered by a glass panel A⁴, and provides a sight opening for the purpose as will appear later on. In the upper end of the casing is arranged a hopper A⁵, which extends entirely across the casing, and is of a size to conveniently hold a pile of checks. The bottom A⁶, of the hopper inclines from the rear to the front of the machine, but stops short of the front, leaving a passage-way A⁷, for the passage of the checks, and which is formed by a divisional plate A⁸, that extends from the hopper and is connected at its lower end to a horizontally arranged divisional plate or bottom A⁹. The back of the casing between the bottom A⁹, and the bottom of the hopper is closed by a suitable hinged back A¹⁰.

Secured upon the inner faces of the sides of the casing are bracket-plates b, one of which has a series of hubs b', having smooth bores in which the ends of a series of shafts,

hereafter described, are journaled, and the other, a series of threaded hubs b^2 , in which operate adjustable bearings b^3 , in which the opposite ends of the shafts are journaled and 5 in one set of the said bearings, is journaled a feed-shaft B, having two or more rubber or rubber-faced feed-rollers or disks B', B', which projects slightly into the hopper through openings a, in the forward end of the 10 bottom of the hopper and into the passage-way A⁷, through openings a' produced in the upper end of the divisional plate A⁸, and extending through openings a³, in the front of the casing, are segregating disks C, C, carried 15 by a suitable support C', which is secured at its ends to the sides of the casing and the faces of these disks slightly contact with the periphery of the feed-rollers and are designed to prevent more than one check 20 at a time being delivered through the passage-way A⁷.

The shaft carrying the feed-rollers B', B', has a pinion B², held thereon adjacent one end, which is meshed by an idle pinion D, of 25 even size, that is journaled upon a stub-shaft projecting from one of the bearing plates b, and engaging this idle pinion, is another pinion E', held upon a shaft E, which is journaled at one end in one of the 30 adjustable bearings b², and at its opposite end in a tubular sleeve F, hereinafter referred to. The pinion E, is meshed by a mutilated gear G, the teeth of which extend around the periphery being equal in number to those of 35 the pinions. This gear G, is mounted upon a shaft G', that is journaled at one end in one of the adjustable bearings and at its opposite end in a bracket-arm b⁴, projecting from the side of the casing and has upon its ex- 40 treme outer end a pinion G², that is meshed by a worm-gear H, carried by a shaft H', whose opposite end is provided with a pinion H², that is meshed by a worm-gear I, held upon the shaft of a motor I'. The shaft H', 45 is journaled in an extension of the bracket b⁴, and in a bracket secured to, and projecting from the end of the motor-frame.

Upon one side of the mutilated gear is a cam disk J, which may be cast integral with 50 the gear or secured thereto in any suitable manner, and engaging the cam is an anti-friction roller k, journaled upon a lever-arm K, that projects from a rock-shaft K', held in suitable hubs formed upon the plates b. 55 This rock-shaft has a series of depending rack-arms L, fixedly held thereon and which extend downwardly and have their lower ends terminate in forwardly projecting fingers L', which normally rest immediately 60 adjacent the lower end of the glass panel A⁴. The roller k, of the lever-arm K, is held into engagement with the cam by a spring k', so that when the cam has been revolved past the roller, the rack-arms will be projected 65 into the lower end of the passage-way

and in position to catch and hold a check so that it may be read through the sight-opening.

The shaft E, before referred to carries a stamping cylinder M, which is fixedly secured 70 to the shaft and revolves therewith and the tubular sleeve F, in which one end of the shaft is journaled is revolvably held within a second tubular sleeve N, that projects into, and is engaged by the end of the cylinder. 75 The sleeve F, projects at each end past the sleeve N, and has its inner end provided with a disk F', upon which is held an endless belt F², which passes through slots formed in the periphery of the cylinder and around a bar 80 F³, which is produced by the slots. This belt has numerals formed thereon or secured thereto, the denominations of which range from 1 to 31 and represent the days of the month. At the outer end the sleeve is provided 85 with a knob-handle F⁴, by which the sleeve is revolved to shift the belt to cause the proper numeral to be held upon the bar.

Adjacent the handle F⁴, is a disk F⁵, having graduation marks which are numbered to 90 correspond with the numerals of the belt and by which the operator can see what numeral of the belt is exposed. The tubular sleeve N, also has a disk N', upon its inner end around which passes an endless belt N², 95 which also passes through the slots in the periphery of the cylinder and over the bar F³. This belt has abbreviations of the twelve months stamped upon or secured thereto and in order to operate this shaft, I provide its 100 outer end with a disk N³, the face of which has a series of graduation marks which may be numbered from 1 to 12 to denote the months in the same manner as the graduation upon the disk F⁵. The edge of the disk 105 N³, is milled to facilitate the turning.

Arranged upon the cylinder and upon opposite sides of the slot is a plate O, having a suitable stamp and also the numerals of the year.

In Fig. 9 of the drawings, I show a portion of a check after it has been stamped and illustrating the form of stamp carrying the usual inscription generally employed in banks.

In order to provide a firm bearing surface for the stamp cylinder, I journal a shaft P, in suitable brackets held upon the ends of the casing and upon which is held a platen roller or cylinder P', of either rubber or any suitable material and which projects through an opening p, produced in the front of the casing into the passage-way, and against the stamp cylinder or roller. The platen roller, its shaft, the segregating disks, and its supports are incased by a suitable plate Q, held upon the front of the casing.

An inking-pad R, is held into engagement with the periphery of the cylinder by bracket-arms R', which are suspended from 125

110

115

120

125

130

the shaft B, and one of these bracket-arms also engages the cylinder shaft E, and the other arm, the tubular sleeve N, said bracket arms forming an intermediate support for 5 the shaft E, and the inner ends of the tubular sleeves.

In practice, the motor is connected to the current wires in any suitable manner, but I propose to interpose a switch S, as shown in 10 the Figs. 1, and 4, of the drawings, so that the movement of the motor may be readily and conveniently controlled.

The manner in which my machine is used and its operation is as follows: When the 15 aggregate amount of a certain number of checks is to be ascertained by the use of an adding machine they are first properly assembled and placed in the hopper A⁵, so that the lower-most check will engage the feed 20 disks B', the switch is then thrown to start the motor which will impart motion through the train of gears to the feed-roller shaft and the stamping cylinder shaft, and the moment the feed-rollers begin to move, they 25 will draw the lower-most check of the pile down through the passage-way A⁷, into engagement with the stamping cylinder and platen roll, through which it will be drawn and stamped and finally allowed to drop 30 down upon the fingers of the rack-arms L, where it will be temporarily retained until the cam carried by the mutilated gear will operate to rock the shaft and draw the lower ends of the arms into the slots T, produced in 35 the lower end of the divisional plate A⁸. When motion is first imparted to the mutilated gear, the feed-rolls and the stamping cylinder will be first operated to feed the check and during this operation, the rack- 40 arms will be allowed to remain in their normal position, but the moment the revolution of the disks and cylinder is stopped, the arms will be operated as before described. This arrangement provides for an intermittent 45 removal of the checks from the hopper and also allows the preceding check to be held adjacent the sight opening in full view of the operator while the succeeding check is passing through the stamping cylinder and platen roll or cylinder, but before the succeeding 50 check has been released, the arms are withdrawn through the slots in the divisional plates when the checks will be wiped or forced therefrom and allowed to drop into 55 a suitable receptacle held in the bottom of the casing which is shown in the drawing as a basket U.

By the use of the segregating disks, it will be seen that only one check is permitted to 60 be withdrawn from the hopper and should two or more checks adhere to each other, the upper ones will be retarded by the disks and only the lower one be permitted to pass down through the passage-way.

65 From the fore-going, it will be seen that I

provide an exceedingly, cheap, simple, and highly efficient device for the purposes stated, and while I have described my machine and illustrated it for use in banks, I desire it understood that I do not limit myself 70 to this particular use as it may be used in department stores for stamping the slips or checks used by the clerks in making sales and in fact in many other instances either in connection with adding machines or for 75 the sole purpose of stamping or indorsing checks and slips of various nature.

Having thus fully described my invention, what I claim as new, and desire to secure by Letters Patent is:—

1. A check displaying device comprising a casing having a hopper and a sight opening below the hopper, means for successively passing checks from the hopper and bringing them into alinement with the sight opening, 85 holding means adapted to retain the check before the sight opening stamping devices for stamping checks during their passage from the hopper to the holding means and means for automatically withdrawing the 90 holding means after a predetermined interval of time.

2. A device of the kind described comprising a check holding receptacle, means for successively withdrawing one check at a 95 time from the said receptacle, visible check holding means adapted to receive the check after it has been withdrawn from the receptacle, means for stamping the checks after they have been withdrawn from the hopper 100 and means for discharging the check from the receiving means after a predetermined time.

3. In a check displaying device comprising a casing provided with a hopper and a sight 105 opening below the hopper, feeding means for successively passing checks from the hopper and bringing them into alinement with the sight opening, a segregating device co-acting with the feeding means, stamping devices 110 for engagement with the checks, holding means adapted to retain the check before the sight opening, and means for automatically withdrawing the holding means after a predetermined interval of time.

4. The combination of a casing having a sight opening and a hopper, feeding devices arranged in the casing and projecting into the hopper, segregating devices held adjacent the feeding devices, a stamping cylinder, 120 rack-arms alining with the sight opening, and means for operating the feeding devices, stamping cylinder, and rack-arms.

5. The combination of a casing having a sight opening and a hopper, intermittently 125 operating feeding disks mounted within the casing, an intermittently operated stamping cylinder arranged adjacent the disks, means for simultaneously operating the feeding disks and stamping cylinder, intermittently 130

operated rack-arms, and means for operating the rack-arms alternately with the feeding disks and stamping cylinder.

6. The combination of a casing having a sight opening and a hopper, feeding disks operatively held within the casing and extending into the hopper, segregating disks held adjacent the feeding disks, a stamping cylinder operatively held within the casing, 10 and a platen roller or cylinder co-acting with the stamping cylinder, rack-arms operatively held within the casing below the stamping cylinder, and means for operating the feeding disks, stamping cylinder, and rack-arms, 15 the said means imparting an alternate movement to the rack-arms with respect to the feeding disks and stamping cylinder.

7. A machine of the kind described, comprising a casing having a sight opening and a 20 hopper, a shaft carrying feeding disks journaled in the casing, a shaft carrying a stamping cylinder journaled in the casing, pinions carried by the shafts, an idle pinion meshing the first mentioned pinions, a rock-shaft 25 having a lever-arm and rack-arms, a mutilated gear engaging the pinion upon the stamping cylinder shaft, and having a cam that engages the lever-arm of the rock-shaft, and means for rotating the mutilated gear, 30 substantially as specified.

8. A machine of the kind described, comprising a casing having a sight opening and a hopper, a shaft carrying feeding disks journaled in the casing, segregating disks held 35 adjacent the feeding disks, a shaft carrying a stamping cylinder journaled in the casing, pinions carried by the shafts, an idle pinion meshing the first mentioned pinions, a rock-shaft having a lever-arm and rack-arms, a 40 mutilated gear engaging the pinion upon the stamping cylinder shaft, and having a cam that engages the lever-arm of the rock-shaft, and means for rotating the mutilated gear substantially as specified.

45 9. A machine of the kind described, comprising a casing having a sight opening in its front face and a hopper in its upper end, a divisional plate providing a passage-way that communicates with the hopper, a shaft 50 carrying feeding disks journaled in the casing, a shaft carrying a stamping cylinder also journaled in the casing, the said feeding disks and stamping cylinder having their peripheries projecting into the said passage-way, 55 segregating disks co-acting with the feeding disks, and a platen roller co-acting with the stamping cylinder, a rock-shaft journaled within the casing and having rack-arms which project into the lower end of the 60 passage-way, and common means for operating the feeding disks and stamping cylinder, and for operating the rock-shaft to withdraw the rack-arms from the passage-way, said means 65 imparting an alternate movement to the

rock-shaft with respect to the feeding disks and stamping cylinder.

10. A machine of the kind described, comprising a casing having a sight-opening in its front face, and a hopper in its upper end, a divisional plate arranged within the casing 70 and adjacent the front face, a shaft carrying feeding disks journaled in the casing, the peripheries of which extend through slots formed in the bottom of the hopper and the divisional plate, segregating disks held adjacent the feeding disks, a shaft carrying a stamping cylinder journaled within the casing below the first mentioned shaft, the periphery of the stamping cylinder projecting through an opening produced in the divisional plate, a rock-shaft journaled in the casing and having depending rack-arms 75 which project through slots in the divisional plates and into the lower end of the passage-way, pinions carried by the shaft having the feeding disks and the cylinder shaft, an idle pinion meshing the said pinions, a shaft carrying a mutilated gear journaled in the casing, said gear meshing the pinion of the cylinder shaft, a cam carried by the gear and 80 adapted for engagement with a lever-arm extending from the rock-shaft, and means for operating the shaft of the mutilated gear substantially as specified.

11. A machine of the kind described, comprising a casing having a sight opening and a hopper, feeding disks operatively held within the casing and projecting into the hopper, segregating disks carried by the casing and held adjacent the feeding disks, a stamping 95 cylinder arranged within the casing, means for simultaneously operating the said disks and cylinder, rack-arms held within the casing and normally held parallel to the sight opening, means for operating the feeding 100 disks and stamping cylinder, and means for operating the said arms alternately with the operation of the said disks and cylinder.

12. A machine of the kind described, comprising a casing having a sight opening in its front and a hopper at its upper end, a divisional plate arranged within the casing adjacent the front and providing a passage-way, a shaft journaled within the casing and having feeding disks secured thereto, the peripheries of which extend into the hopper and passage-way, segregating disks held upon the casing and projecting into the passage-way and co-acting with the feeding disks, a shaft carrying a stamping cylinder journaled 110 in the casing, the periphery of the cylinder extending into the said passage-way, a platen roller held upon a shaft that is journaled in the casing and having its periphery contacting with the periphery of the stamping cylinder, a rock-shaft journaled in the casing 115 and having rack-arms depending therefrom which extend through slots in the divisional 120

plate, said arms being normally held in parallel relation to the sight opening, a lever-arm projecting from the rock-shaft, pinions held upon the shaft of the feeding disks and 5 the cylinder shaft, an idle pinion meshing the said pinions, a gear journaled within the casing and adapted to mesh the pinion carried by the cylinder shaft, a cam surface formed upon the gear and engaging the lever-arm of 10 the rock-shaft, a worm-pinion arranged upon the shaft carrying the mutilated gear, a motor held within the casing, the shaft of which is provided with a worm-wheel, and a shaft carrying a worm-wheel which meshes with 15 the worm-pinion, and a worm pinion which meshes the worm-wheel of the motor-shaft.

13. A machine of the kind described, comprising a casing having a sight opening in its face and a hopper at its upper end, a horizontally disposed divisional plate arranged above the lower end of the casing, and a vertically arranged divisional plate that extends from the forward end of the hopper to the 20 said horizontal divisional plate; the said vertically disposed plate providing a passage-way which extends from the hopper to the lower end of the casing, a shaft journaled within the casing, feeding disks carried by the shaft, a stamping cylinder held upon a 25 shaft that is journaled in the casing, a rock-shaft journaled in the casing and having rack-arms depending therefrom which extend into the lower end of the passage-way, pinions carried by the first and second mentioned shafts, an idle pinion meshing the said 30 pinions, a shaft journaled in brackets carried by the casing, a mutilated gear carried by the last mentioned shaft and meshing the pinion of the cylinder shaft, a cam formed upon the 35 side of the gear and adapted for engagement by a lever-arm extending from the rock-shaft, and a motor held upon the horizontal divisional plate and operatively connected to the mutilated gear shaft substantially as 40 specified.

14. A machine of the kind described, comprising a casing, a shaft journaled at one end in a bracket carried by the casing and at its opposite end in an adjustable bearing held in 45 the opposite side of the casing, feeding disks held upon the shaft, a second shaft journaled at one end in the casing and at its opposite end in a tubular sleeve which in turn is held in a second tubular sleeve that is journaled at 50 one end in the casing, a stamping cylinder held upon the second mentioned shaft, one end of the stamping cylinder providing a bearing for the second mentioned tubular sleeve, disks arranged upon the inner ends of 55 the said tubular sleeves, said disks having belts operating thereon which extend through the periphery of the cylinder for the purpose specified, a rock shaft journaled at one end in a stationary bearing carried by the casing 60

and at its opposite end in an adjustable bearing held in the opposite side of the casing, rack-arms depending from the rock-shaft, and means for operating all of the shafts substantially as specified.

15. A machine of the kind described, comprising a casing having a sight opening and a hopper, a shaft carrying feeding disks projecting into the hopper, segregating disks co-acting with the feeding disks, a shaft carrying a stamping cylinder journaled in the casing, endless belts having type surfaces operatively held within the cylinder, said belts operating through slots produced in the periphery of the cylinder, and means for operating the belts, a rock-shaft carrying rack-arms 70 75 journaled in the casing, and means for intermittently operating the shaft having the feeding disks and the cylinder shaft, and means for intermittently operating the rock-shaft, said rock-shaft being operated alternately with respect to the disks and cylinder 80 85 substantially as specified.

16. A machine of the kind described, comprising a casing, a shaft having feeding disks journaled in the casing, segregating disks co-acting with the feeding disks, a shaft carrying a stamping cylinder journaled in the casing, tubular sleeves encircling one end of the shaft and projecting into the cylinder, the ends of the said sleeves having disks arranged 90 95 thereon, endless belts having type surfaces held upon the disks and operating through slots formed in the periphery of the cylinder, a knob formed upon the end of one sleeve and a disk held upon the end of the other sleeve, 100 a platen roller co-acting with the stamping cylinder, an ink roller held for engagement with the stamping cylinder, a rock-shaft journaled in the casing and having rack-arms depending therefrom, and means for operating the feeding disk shaft, the stamping cylinder shaft, and the rock-shaft substantially as specified. 105

17. A machine of the kind described, comprising a casing having a sight opening and a hopper, a vertically disposed divisional plate 110 arranged within the casing adjacent the front, said divisional plate providing a passage-way which communicates with the hopper, a shaft journaled in the casing, feeding disks held upon the shaft and extending into 115 the forward end of the hopper and the upper end of the passage-way, segregating disks held in the casing adjacent the feeding disks, a shaft carrying a stamping cylinder journaled in the casing and having its periphery 120 extending into the passage-way, a platen roller co-acting with the stamping cylinder, endless belts mounted within the stamping cylinder and projecting through slots in the periphery of the cylinder, and means for 125 operating the belts, a rock-shaft journaled in the casing and having depending rack-arms which project through slots formed in

the said divisional plate, said arms being normally held adjacent the sight opening, and means for intermittently operating the feeding disk shaft, the stamping cylinder 5 shaft, and means for intermittently operating the rock-shaft, said feeding disk shaft and cylinder shaft being operated alternately with the operation of the rock-shaft.

18. A machine of the kind described, comprising a casing consisting of the base, sides, and front, and having a hopper arranged in the upper end, and a horizontally disposed divisional plate providing a bottom near its lower end, a vertically disposed divisional 15 plate extending from the forward end of the hopper to the said bottom and providing a passage-way which communicates with the hopper, the front of the casing having a sight opening arranged therein, feeding disks operatively held within the casing and projecting 20 into the forward end of the hopper and the upper end of the passage-way, a stamping cylinder operatively held within the casing and projecting into the passage-way below the feeding disks, rack-arms arranged within 25 the casing and projecting into the lower end of the passage-way, said arms being normally held adjacent the sight opening, segregating disks co-acting with the feeding disks and a 30 platen roller co-acting with the stamping cylinder, means for intermittently and simultaneously operating the feeding disks, and stamping cylinder, and means for intermittently operating the rock-shaft to withdraw 35 the rack-arms away from the sight opening, said rock-shaft being operated al-

ternately with respect to the feeding disks and stamping cylinder.

19. A device of the kind described comprising a casing having a hopper and sight 40 opening, rack arms arranged adjacent the sight opening, the feed roller adapted to feed checks successively from the hopper to the rack arms and a mutilated gear adapted to operate the feed rollers and having a cam 45 oppositely arranged with respect to the gear teeth and adapted to operate the rack arms.

20. In a machine for holding, stamping, and displaying checks, and the like, the combination of an intermittently operated feeding device, an intermittently operated stamping device, and means for holding a check after it has been stamped, said means being operated to release the check when the feeding device and stamping device are inactive. 50

21. In a machine for holding, stamping, and displaying checks, and the like, the combination with a casing having a sight opening, of an intermittently operated feeding device, an intermittently operated stamping 60 cylinder, and means arranged adjacent the sight opening for engagement by the check after it has passed the stamping cylinder for holding it opposite the sight opening, said means being operated to release the check 65 when the said feeding device and stamping cylinder are inactive.
